UNITED STATES PATENT OFFICE.

FRIEDRICH ADLER, OF HAMBURG, GERMANY.

STENCILING AND DYEING FABRICS AND THE LIKE.

Application filed November 5, 1925, Serial No. 67,038, and in Germany November 7, 1924.

My invention refers to the art of producing coloured patterns on porous materials such as fabric and the like and more especially to the manner of stenciling which originated in Java and is commonly known as batik dyeing. As is well known to those skilled in the art this Javan method is based on the impregnation of those parts of the fabric, which shall not be dyed, with wax, paraffin or some other resist, preferably by immersing a metal stencil in hot fluid wax and then placing it onto the fabric, the fluid wax entering the fabric and protecting the impregnated portion against the dye solutions. This method can be easily practised at the average temperature of 40° C., prevailing as a rule in a hot country like Java, the more so as the wax produced by the Javan bees remains fluid for a longer period than the wax of the bees reared in Europe and America. In consequence of the materially lower average temperature prevailing in these latter countries and of the more rapid solidification of the wax the utilization of the Javan batik process encounters serious difficulties both in Europe and America.

Moreover the Javan process does not allow impregnating several layers of fabric or the like at a time and in consequence thereof a piece of fabric impregnated only on one side must be turned over in order to treat the rear side.

It is an object of my invention to overcome all these difficulties and to render the batik dyeing process applicable independently of the temperature of the air and of the melting point of the wax. It is a further object of my invention to render this process adapted for a production on a large scale. It is a further object of my invention to render the process more efficient as regards the quality of the products obtained.

With these and other objects in view I will now proceed to describe my invention and how the same is to be performed, having reference to the drawings which illustrate diagrammatically and by way of example several modes of carrying my invention into practice.

It is based substantially on the step of placing the fabric, paper or the like on a support containing or consisting of wax or other resist and applying heat to those parts of the fabric or the like, which it is intended to impregnate with the wax, so as to protect it from being dyed. The heat will

cause the wax or the like to melt below these parts of the fabric, the fluid wax being then absorbed by these parts. Preferably heat is applied by pressing onto the fabric a metal stencil which has previously been heated to a temperature sufficing to melt some of the wax under the fabric inserted between them.

In the drawings

Fig. 1 is a vertical section illustrating the above mode of proceeding.

Fig. 2 is a similar view illustrating means whereby the method of stenciling can be practised in a continuous manner.

Figs. 3 and 4 are similar views illustrating two modifications of the arrangement shown in Fig. 1.

Referring first to Fig. 1, *a* is a metal stencil, *b* is a piece or web of the fabric to be impregnated and *c* is a sheet of wax, paraffin or the like. By pressing the heated stencil *a* onto the fabric, some of the wax on the surface of *c* is melted and readily absorbed by the fabric. Obviously the stencil *a* can be formed and engraved in any suitable manner in order to produce the pattern desired in each individual case.

In the arrangement disclosed in Fig. 2, *a'* is an engraved metal cylinder which replaces the ordinary stencil and *c'* is a wax cylinder. *b* is the web of fabric travelling between them. Obviously, when the metal cylinder *a* is heated in any suitable manner, it will cause the wax on the surface of cylinder *c* to melt and to be absorbed by the fabric *b* while this latter is pulled through between them.

In the modification illustrated in Fig. 3, *a* is the stencil and *b* the fabric to be impregnated, *c* is a piece of fabric thoroughly impregnated with the resist such as wax, *f* is a piece of oil cloth or the like and *d* is a yielding support formed by a piece of felt or the like. Here the sheet of pure wax shown in Fig. 1 is replaced by a web of porous material impregnated with the resist, which may prove useful in many cases, and this impregnated sheet can be advanced together with the fabric to be impregnated which could not be done as easily in the case of a solid sheet of wax.

In the modification illustrated in Fig. 4 means are provided whereby the piece of fabric or the like to be impregnated is prevented from sticking to the wax support when this latter solidifies. If the fabric

were allowed to stick to the wax one side of the layer of resist would be torn and this part of the fabric could be attacked by the dyestuff solution. In order to prevent this, ²⁰ means such as clamping blocks *e* are placed on the layer of wax *c*, these clamping blocks holding the fabric *b*, which shall be impregnated, in stretched condition above the wax body so as to keep it in spaced relation there-
 to. If pressure is now applied onto the fabric by means of the stencil *a* this part of the fabric is pressed onto the wax support in order to be impregnated but on being relieved of the pressure the fabric will be de-
 tached at once from the wax by its elasticity before the wax has solidified.

Obviously several superposed layers of fabric, paper or the like can be acted upon simultaneously by the stencil and it is there-
 fore possible to insert a folded piece of fabric or the like between the stencil and the wax and by a single impression of the stencil to impregnate several portions of the piece of fabric in a strictly identical and sym-
 metrical manner.

Inasmuch as the wax absorbed by the fabric solidifies at once, the fabric or the like can be dyed without any loss of time

and after having dried can be impregnated in another place.

The products obtained by this process are not only equal to but in most cases superior to those produced by hand and in the ordinary manner practised in Java.

I wish it to be understood that I do not ²⁵ desire to be limited to the exact materials, operations and means described and illustrated, for obvious modifications will occur to a person skilled in the art.

I claim:—

1. Device for partly impregnating fabric with wax comprising a support containing wax, a member adapted to be heated and pressed onto said support and means for holding the fabric to be impregnated above ⁴⁵ and in spaced relation to said support.

2. Device for partly impregnating fabric with wax comprising a web support containing wax, a member adapted to be heated and pressed onto said support and means for holding the fabric to be impregnated above ⁵⁰ and in spaced relation to said support.

In testimony whereof I affix my signature.

FRIEDRICH ADLER.
